(57) **CLAIM**

The ornamental design for audio video shelving unit, as shown and described.

DESCRIPTION

FIG. 1 is a front perspective view of the subject audio video shelving unit;

FIG. 2 is a front view thereof;

FIG. 3 is a rear view thereof;

FIG. 4 is a top plan view thereof;

FIG. 5 is a right side view thereof (the left side view is a mirror image of the right side view); and,

FIG. 6 is a front perspective view of a second embodiment of the subject audio video shelving unit.

The broken lines shown on the drawings are included for the purpose of illustration and form no part of the claimed design.
